UNITED STATES PATENT OFFICE

2,565,816

VAPORIZER

Sam P. Jones, Dallas, Tex.

Application December 20, 1945, Serial No. 636,202

2 Claims. (Cl. 257—241)

1

This invention relates to new and useful improvements in vaporizers.

One object of the invention is to provide an improved vaporizer particularly adapted to vaporize volatile liquids, such as hydrocarbon motor fuels and to prevent superheating of the vapors or gas.

A particular object of the invention is to provide an improved vaporizer that will vaporize a volatile liquid, especially under low pressures, and deliver a vapor or gas which will be more uniform in temperature, throughout a range of operation, than is possible with vaporizers now in common use.

Another object of the invention is to provide an improved vaporizer that will not crack or burst when used with water or a water bearing liquid.

Still another object of the invention is to provide an improved vaporizer wherein a reduction in pressure results in the release of a large volume of vapor or gas and also wherein, substantially no reduction in pressure results in the release of vapor or gas immediately upon contact of the volatile liquid with the heat exchange surface.

A further object of the invention is to provide an improved vaporizer including an enclosure having a liquid vaporizing chamber and a heat transfer chamber separated from the first chamber by a heat exchange wall, together with means in the chambers for causing fluids flowing therethrough to take circuitous paths or whereby, vapors evolved in the vaporizing chamber may by-pass the circuitous-path means.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is an elevation of a vaporizer constructed in accordance with the invention and connected with component operating elements.

Fig. 2 is a longitudinal vertical sectional view of the vaporizer.

Fig. 3 is a horizontal cross-sectional view indicated on the line 3—3 of Fig. 2, and

Fig. 4 is a transverse sectional view indicated on the line 4—4 of Fig. 2.

In the drawings, the numeral 10 designates a flat, rectangular body, closed by a relatively flat top cap 11 and a relatively flat bottom cap 12, having their edges flush with the outer surface

2

of the body. Rectangular sealing gaskets 13 are interposed between the marginal walls 14 of the body and the caps, the inner edges of said gaskets conforming to the inner contours of said marginal walls. The walls 14 are formed with inwardly projecting, upright bosses 15, 15' and 16 which have screw-threaded sumps 16 in their upper and lower ends to receive machine screws 17 passing through the caps and gaskets, whereby said caps are detachably secured to the body.

The body is divided by a horizontal partition or wall 18, into an upper, vaporizing chamber A and a lower, heat transfer chamber B. The partition is integral with the walls 14 and bosses 15 and the upper chamber is preferably deeper than the lower chamber. In the upper chamber, upright transverse baffles or fins 19 and 20, respectively, are disposed in alternate order. The baffles 19 have their ends terminating short of the walls 14, but adjacent thereto and are located between the bosses 15. The baffles 20 are integral with the bosses 15 and extend therefrom with their ends terminating short of the longitudinal center of the body, thus providing gaps 21 or openings 21, between their adjacent ends.

Beyond each end baffle 19, short baffles or deflectors 22 extend from the adjacent bosses 15' and each deflector is directed at an angle to the transverse axis of the body, toward the adjacent baffle 19. Between the baffles 22 at each end of the body, oppositely facing upright guards 23 are provided. The baffles, deflectors and guards are all preferably made integral with the partition 18 and have their upper edges flush with the upper edge of the body wall 14 and they provide circuitous flow paths longitudinally along each side of the body, as is indicated by the arrows in Fig. 2. The baffles, deflectors and guards which have been described are located in the chamber A and these elements are duplicated in the chamber B below the partition 18 and vertically aligned therewith; therefore, the same reference numerals are applied to the lower baffles, deflectors and guards.

The cap 11 has an upstanding internally screw-threaded inlet boss 24 at one end and a similar outlet boss 25 at its opposite end. These bosses are disposed so as to communicate with the spaces defined by the guards 23. An inlet boss 26 and an outlet boss 27 are similarly located on the cap 12. The bottom cap 12 may have an internally screw-threaded boss 27' to receive a drain plug 28. By observing Figs. 2 and 4 it will be observed that the top cap 11 has an elongate shallow recess 29 extending from end

to end thereof; while the bottom cap has a similar recess 30. These recesses form by-passes between the inlets and outlets.

In using the vaporizer the inlet boss 24 of the vaporizing chamber A is connected with a fuel supply line C, whereby liquid fuel, such as a butane-propane mixture, may flow to said chamber. This line may include a pressure regulator D. A gas delivery line E is connected to the boss 25 and preferably includes a pressure regulator F. A supply hose or other suitable conductor G is connected with the boss 26 for supplying a heating fluid to the heat transfer chamber B; while a discharge hose H is connected to the outlet boss 27.

The heat transfer medium must be of such temperature as to produce the necessary heat to vaporize the volatile liquid. Where the vaporizer is used with an internal combustion engine, the hose G and the hose H may be connected with the water circulating system thereof or in the exhaust system of the engine. It is obvious that the circulating heat transfer fluid will heat the body 10 including the baffles 19 and 20, deflectors 22 and guards 23, through the partition 18, which acts as a heat exchange element. The volatile liquid entering the chamber A will be arrested by the guard 23 below the inlet 24 and then caused to flow through the circuitous paths indicated by the arrows in Fig. 3. This delayed travel will give ample time for vaporization. A similar travel will be taken by the fluid in the chamber B, so that the heat exchange is equally distributed.

Gas or vapor will be generated or evolved in accordance with the supply of liquid fuel to the chamber A and thus, a small or limited supply, as when the engine is under a light load, will produce a small or limited delivery of gas. As the engine load increases the liquid supply increases and thus the amount of gas delivered, increases in proportion thereto. Where the fuel liquid supply is small, the liquid may not reach the ends of the circuitous path; however, the vapors will rise to the by-pass recess 29 in the top cap 11 and flow to the outlet 25.

It is obvious that since the vapors or gas rise out of the circuitous path formed by the baffles, into the by-pass recess 29, they are out of heat exchange relation with the partition and said baffles. By this arrangement the vapors, as soon as they are evolved or generated, are removed from the heat transfer medium and are thus not superheated. Such vapors will by-pass directly to the outlet 25 and form a highly desirable fuel for an internal combustion engine. If the supply of fuel liquid is increased or is large, the chamber A will be filled to a greater extent and more vapors will be produced. The by-pass 29 is important because it permits vapors rising at various points in the circuitous paths, to flow directly to the outlet 25 and not be superheated while so flowing.

It is pointed out that the pressure of the inflowing fuel liquid may be reduced in the chamber A and such reduction would enhance the release of vapors; some pressure being maintained in said chamber. If the inflowing liquid is under merely a flowing pressure and substantially no pressure reduction takes place in the chamber A, then vaporization will take place substantially as such liquid contacts the heating

surfaces. The gas or vapor delivered is ready for use and after once reaching the by-pass recess 29, is not required to flow an elongated path; thus there is no unnecessary superheating.

If water is used as the heat transfer medium the danger of freezing is eliminated. In the construction herein set forth freezing would occur from one side only and there is no tendency to trap water and cause a rupture of the vaporizer.

Tests have shown that when the vaporizer is subjected to freezing, no harmful results have occurred.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A vaporizer including, a body having a substantially horizontal heat exchange partition, alternate substantially vertical baffles on each side of said partition, and caps secured to the body and enclosing the partition and baffles therebetween, said caps having spaced inlets and outlets substantially perpendicular to the planes of said caps, and each of said caps having a by-pass recess on its inner side, the inlets and outlets of the caps opening directly into said recesses, and the baffles being in the path of the media flowing between the inlets and the outlets and being arranged to provide tortuous flow paths for said media.

2. A vaporizer including, a body, a horizontal partition within the body, vertical baffles extending upwardly and downwardly from the partition and terminating substantially flush with the top and bottom edges of said body, a top cap secured on the upper edge of the body having an inlet at one end and an outlet at its opposite end, said inlet and outlet being entirely above the upwardly extending baffles, and a bottom cap secured on the lower edge of the body and having an inlet at one end and an outlet at its opposite end, said latter inlet and outlet being entirely below the downwardly extending baffles, the top cap having a longitudinal by-pass recess overhanging and being above the upwardly extending vertical baffles, and the bottom cap having a longitudinal by-pass recess underlying and being below the vertical baffles extending downwardly from the partition, and the baffles being in the path of the media flowing between the inlets and the outlets and being arranged to provide tortuous flow paths for said media.
